UNITED STATES PATENT OFFICE.

HUGO BORCHARDT, OF CHARLOTTENBURG, GERMANY.

AUTOMATIC FIREARM WITH TOGGLE-JOINT.

1,160,831.

Specification of Letters Patent. Patented Nov. 16, 1915.

Application filed February 2, 1914. Serial No. 816,045.

To all whom it may concern:

Be it known that I, HUGO BORCHARDT, citizen of the United States of America, residing at No. 31 Kantstrasse, Charlottenburg, near Berlin, Germany, have invented certain new and useful Improvements in Automatic Firearms with Toggle-Joints, of which the following is a specification.

It is known in connection with automatic fire-arms to lock the trigger, when the breech is open, by a member controlled by the breech bolt. The action of the locking member is thus directly dependent on the position of the breech bolt and is therefore not exact, because a comparatively long movement of the breech bolt is necessary in order to engage or disengage the detent.

This invention relates to a detent for automatic fire-arms with toggle joint, wherein the said drawbacks are obviated by rendering the action of the detent not dependent directly on the movement of the breech bolt but on the movement of the toggle joint. This toggle joint, and especially its central point, covers, during the first opening movement of the breech, a distance which is a multiple of that of the breech bolt. It can therefore be attained with the greatest degree of accuracy that the trigger is released only when the breech is actually completely closed.

The invention is shown by way of example in the accompanying drawing.

Figure 1 is a broken side elevation showing the locking device with closed breech *i. e.* inoperative and Fig. 2 is a cross-section on line A—A of Fig. 1. Fig. 3 is a side view of the engaged detent with breech not completely closed. Fig. 4 is a longitudinal view partly in section showing the trigger mechanism. Fig. 5 is a horizontal sectional view of a part of the mechanism shown in Fig. 4.

In the constructional form of the invention illustrated in the drawings, the trigger locking member co-operates with a rod *b* connecting the sear *s* to the trigger *i* and slidably mounted in the breech casing *c*.

The sear *s* comprises two parts *s*¹, *s*², one of which, *s*¹, is pivoted at *s*³ to the breech casing *c* and co-operates with the connecting rod *b*, while the other part, *s*², engages the firing pin *p* and is rotatably and slidably mounted in the part *s*¹.

In the cocked position (see Fig. 5) the sear member *s*² is held by the pressure of the spring *p*¹ in the foremost position. When

the trigger *i* is pulled for firing the connecting rod *b* is shifted in the forward direction and rocks the sear member *s*¹, which by means of its fore end underlying the sear member *s*² rocks this latter so that it releases the firing pin. The sear member *s*² is now free for longitudinal rearward displacement under the influence of its springs *s*⁴, *s*⁵. In displacing in this manner the sear member *s*² comes free from the supporting fore end of the sear member *s*¹, so that it can be rocked by the spring *s*⁶ into the engaging position.

When the firing pin returns with the breech mechanism into the forward position, the firing pin is again caught by the sear member *s*² and this latter is repressed into its initial position (see Fig. 5) by the spring *p*¹ of the firing pin.

The trigger locking member consists of a safety slide *a*, which is slidably mounted vertically to the longitudinal axis of the firearm in the breech casing *c*. The lower, rectangularly bent down end of the safety slide *a* engages under the connecting rod *b*, which is provided behind the safety slide with an abutment *b*¹ and in front of the safety slide with an arm *b*² engaging under the latter. The upper end of the safety slide bears, when the breech is closed, on the inner surface of the annular shoulder *e* of the middle joint of the toggle member *f*, *g*. A spring *d* presses upon the lower end of the safety slide *a*.

When the breech is not completely closed (Fig. 3), the safety slide *a* is kept in a raised position by means of the spring *d*, its lower arm being situated in front of the abutment *b*¹ of the connecting rod *b*. The sear cannot therefore be moved forward *i. e.* the firing pin cannot be released. When the breech is completely closed (Fig. 1 and 2) the safety slide *a* will be depressed by the shoulder *e* against the action of the spring *d* so that the lower arm of the safety slide is out of reach of the abutment *b*¹ of the connecting rod *b*. The trigger mechanism is now released. During the downward movement of the safety slide *a*, the arm *b*² of the connecting rod serves as an abutment for limiting this movement. Only a very small movement of the safety slide corresponding to the height of the abutment *b*¹ is necessary for the release of the connecting rod. This movement is a multiple of that movement or distance, which is covered by the breech

bolt in the same time. The détent can thus only be released at the last moment of the closing movement *i. e.* the trigger will only be released when the breech is completely closed.

It will be clear that various changes can be made in the details of the construction and arrangement and that the invention is not limited to the precise form and combination of the trigger lock and trigger mechanism shown and described herein.

I claim:—

1. In an automatic firearm the combination of a toggle joint breech mechanism, and means normally locking the trigger mechanism and actuated by the toggle joint to release the trigger mechanism at the instant that the breech is closed.
2. In an automatic firearm the combination of a toggle joint breech mechanism, and means under control of the central joint of the toggle members for locking the trigger mechanism when the breech is open.
3. In an automatic firearm the combination of a toggle joint breech mechanism; and

locking means for the trigger mechanism adapted to be moved by the toggle joint in a direction vertical or almost vertical to the direction of movement of the breech block to unlock the trigger mechanism.

4. In an automatic firearm having a toggle joint breech mechanism, a slide guided in the breech casing and a spring normally holding said slide in locking engagement with the trigger mechanism, said slide being shifted by the toggle joint to release the trigger mechanism at the instant that the breech is closed.

5. An automatic firearm comprising a toggle joint breech mechanism, a trigger mechanism, and means under control of the toggle joint to lock the trigger mechanism when the breech is open.

In testimony whereof I have affixed my signature in presence of two witnesses.

HUGO BORCHARDT.
